SAFETY GRIP

Lee Welch, Houston, Tex.

Application May 21, 1943, Serial No. 487,909

2 Claims. (Cl. 294—104)

The invention relates to a safety grip and more particularly to what is generally termed bulldog clamps.

The primary object of the invention is the provision of a clamp of this character wherein horizontally disposed work can be firmly and securely gripped thereby for the hoisting of the same from said horizontally disposed position, the clamp being a refinement over the subject-matter of Letters Patent No. 2,308,485, issued January 19, 1943.

Another object of the invention is the provision of a clamp of this character which is safe in that it will positively grip the work particularly sheet metal plates when at rest in a horizontal position, or approximately so.

A still further object of the invention is the provision of a clamp of this character which involves detail structural set up to assure simplicity of operation.

A still further object of the invention is the provision of a clamp of this character which is simple in construction, strong, durable, thoroughly reliable and efficient in operation, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention and pointed out in the claims hereunto appended.

In the accompanying drawing:

Figure 1 is a side elevation of the clamp constructed in accordance with the invention and in open position.

Figure 2 is a rear elevation thereof.

Figure 3 is a view similar to Figure 1 showing the clamp in gripping position.

Figure 4 is an edge elevation thereof.

Figure 5 is a top plan view.

Similar reference characters indicate corresponding parts throughout the several views in the drawing.

Referring to the drawing in detail, A designates generally the clamp constructed in accordance with the invention, and involves a substantially horseshoe shaped yoke or head B having spaced parallel side cheeks 10, these being joined by cross rivets 11 and said yoke or head is provided with a mouth opening 12 for accommodating work, the latter indicated by dotted lines in Figures 1 and 3 by way of the reference character C. Fitting the mouth opening 12 is a sta-

tionary jaw 13 having the roughened work engaging surface 14, while disposed between the cheeks 10 at the opening 12 and opposite the said jaw 14 is a swinging jaw 15. This jaw 12 cooperates with the jaw 14 for the clamping of the work C therebetween on the approach of said jaw 15 to the jaw 14. The jaw 15 is pivoted at 16 for swinging movement.

Rearwardly of the mouth opening 12 and arranged between the cheeks 10 is a swinging slotted link 17, it being pivoted at 18 between the said cheeks 10, and this link 17 is formed with a stop projection 19 in the path of an abutment 20 mounted in the cheeks 10 for disposition in the path of the stop projection 19 so as to limit the swing of the link 17 in one direction.

Between the movable jaw 15 and the link 17 is a throw link 21, its connection with the jaw 15 is had by the pivot 22 and its connection with the link 17 is had by the pivot 23 working in the slot 24 in said link 17.

Loosely connected to the pivot 23 is a shackle 25 which is designed for connection with a hoist cable so that through the latter the clamp can be operated for gripping work in the mouth opening 12 and hoisting it from a horizontal or substantially horizontal position as should be obvious.

In the working of the clamp the link 17 under pull upon a cable connected to the shackle 25 throws the stop projection 19 against the abutment 20 and assuming a piece of work C between the jaws 14 and 15 when the stop projection 19 strikes the abutment the link 21 will be caused to travel in the slot 24 in a direction whereby the jaw 15 will move against the work C and thus firmly clamp the latter in the head B and when a continuous pull upon the hoisting cable is had, the piece of work C will be elevated from a horizontal position to a vertical position and to the desired height as may be determined.

What I claim is:

1. A clamp of the character described for suspension from a hoisting cable to lift work edge-wise when in a substantially horizontal position comprising a head having a mouth opening therein for receiving the work, a stationary jaw in the mouth opening, a movable jaw pivoted to the head and cooperating with the stationary jaw for the clamping of the work, a link pivoted to the head and having an elongated slot, a stop on the link, an abutment on the head to be engaged by the stop, and a throw link pivoted to the movable jaw and slidably fitting the slot in said link.

2. A clamp of the character described for suspension from a hoisting cable to lift work edge-wise when in a substantially horizontal position comprising a head having a mouth opening therein for receiving the work, a stationary jaw in the mouth opening, a movable jaw pivoted to the head and cooperating with the stationary jaw for the clamping of the work, a link pivoted

to the head and having an elongated slot, a stop on the link, an abutment on the head to be engaged by the stop, a throw link pivoted to the movable jaw and slidably fitting the slot in said link, and a shackle having engagement with the connection of the throw link with the slot in the first mentioned link.

LEE WELCH.
